(57) **CLAIM**

The ornamental design for a tampon, as shown and described herein.

DESCRIPTION

FIG. 1 is a front, top perspective view of a tampon showing a first embodiment of our design;

FIG. 2 is a rear, bottom perspective view of the first embodiment;

FIG. 3 is a front elevation view of the first embodiment;

FIG. 4 is a rear elevation view of the first embodiment;

FIG. 5 is a left-side elevation view of the first embodiment;

FIG. 6 is a right-side elevation view of the first embodiment;

FIG. 7 is a top plan view of the first embodiment;

FIG. 8 is a bottom plan view of the first embodiment;

FIG. 9 is a front, top perspective view of a tampon showing a second embodiment of our design;

FIG. 10 is a rear, bottom perspective view of the second embodiment;

FIG. 11 is a front elevation view of the second embodiment;

FIG. 12 is a rear elevation view of the second embodiment;

FIG. 13 is a left-side elevation view of the second embodiment;

FIG. 14 is a right-side elevation view of the second embodiment;

FIG. 15 is a top plan view of the second embodiment; and,

FIG. 16 is a bottom plan view of the second embodiment.

The broken lines shown in the drawings represent portions of the tampon that form no part of the claimed design.
